CLAIM

The ornamental design for a ventilator tubing assembly, as shown and described.

DESCRIPTION

FIG. 1 is a front perspective view of a ventilator tubing assembly showing our new design in a condition of use; FIG. 2 is a front elevation view; FIG. 3 is a rear plan view thereof; FIG. 4 is a top plan view thereof; FIG. 5 is a bottom plan view thereof; FIG. 6 is a right elevation view thereof; and, FIG. 7 is a left elevation view thereof.

The ventilator tubing and cord are shown with symbolic breaks in their lengths. The appearance of any portions of the ventilator tubing and cord between the breakaway lines forms no part of the claimed design. The breakaway lines form no part of the claim.

The broken lines depict portions of the ventilator tubing assembly that form no part of the claimed design.

The broken lines showing a ventilator in FIG. 1 depict environmental matter and form no part of the claimed design.
